UNITED STATES PATENT OFFICE

143,115

DESIGN FOR A PLAQUE OR SIMILAR ARTICLE

Beulah Brock Bell, Wilmington, N. C.

Application June 12, 1945, Serial No. 120,035

Term of patent 7 years

(Cl. D29—23)

To all whom it may concern:

Be it known that I, Beulah Brock Bell, a citizen of the United States, residing at Wilmington, in the county of New Hanover and State of North Carolina, have invented a new, original, and ornamental Design for a Plaque or Similar Article, of which the following is a specification, reference being had to the accompanying drawing, forming part thereof,

I claim:

The ornamental design for a plaque or similar article, as shown.

BEULAH BROCK BELL,
